UNITED STATES PATENT OFFICE.

ALBERT EMANUEL GINSBERG, OF LIVERPOOL, ENGLAND.

SAFETY RAZOR.

Application filed April 13, 1923. Serial No. 631,796.

To all whom it may concern:

Be it known that I, ALBERT EMANUEL GINSBERG, a subject of the King of England, and a resident of "Lynwood", Queens Drive, 5 Mossley Hill, Liverpool, in the county of Lancaster, England, have invented certain new and useful Improvements in or Relating to Safety Razors, of which the following is a specification.

10 This invention relates to razors of the safety type, and has for its object to provide a razor or razor portion adapted to contain a plurality of shaving blades which are revolvably disposed within a casing or 15 magazine, means being provided whereby any selected blade may be carried to a position for use or withdrawn into the casing or magazine.

I will further describe my invention 20 with the aid of the accompanying sheets of explanatory drawings which illustrate, by way of example only, one mode of embodying same, the several views being drawn to an enlarged scale.

25 In said drawings:—

Fig. 1 is a longitudinal section of a razor and Fig. 2 a transverse section taken as on line A—A, Fig. 1.

30 Figs. 3 and 4 are outside elevations of 35 the respective end closure members of the razor.

Fig. 5 is a part sectional elevation of the razor when not in use, and

Fig. 6 is a part sectional elevation showing the razor when ready for use.

35 Figs. 7 and 8 are, respectively, elevation and end view of a shaving blade with carrier piece.

Figs. 9 and 10 are views, taken at right 40 angles to each other, of a blade holding device or refill.

Fig. 11 is an inside elevation of one of the end closure members of the razor and part operatively connected therewith.

45 Fig. 12 is a view showing the position of parts when a blade holder with blades is being loaded into the casing or magazine or being removed therefrom.

The component parts of the razor may be 50 conveniently made of brass, nickel and/or aluminum.

Referring now to the drawings, 1 indicates a cylindrical casing or magazine in which there is formed a longitudinal slot 2 at each end whereof is secured to the 55 casing or magazine 1 guide pillars 3, 3, and a lateral groove or channel 27.

shaped to provide a longitudinal slot or groove 4, and the sides whereof are in-turned as indicated at 5, 5, the opening or gap between said inturned portions 5, 5, 60 being equal to the width of the magazine slot 2 with which it is in aligned communication.

Arranged between and secured to the outer portions of said pillars 3, 3, is a 65 toothed guard 6 at the outer ends whereof are formed U stop pieces 7.

Disposed on the exterior of said casing or magazine 1 is a bent or curved cover plate 8 provided with a slot 9 wherethrough 70 extends a screw-threaded spindle piece 10 on which is screwed a nut 11 and a handle 12, said nut 11 being provided for the purpose of preventing displacement of the cover plate when the handle 12 is removed. 13 75 indicates a knob on said plate 8.

At each side of said cover plate 8 there is formed an out-turned strip or tongue 14.

In one end of said casing or magazine there is permanently secured a disc closure 80 15 and at the other end of said casing or magazine there is removably disposed a disc closure 16, said closure 16 being provided with positioning lugs 17 which are adapted to enter slots or recesses 18 provided for 85 their reception in an end of the casing or magazine.

Extending centrally through said casing or magazine 1 is a spindle 19 one end whereof passes through and is supported by the permanent end closure 15 and is provided with a crank handle 20, whilst the other end passes through and is supported by said end closure 16 which is detachably engaged with said spindle 19 by means of a sliding 90 plate 21 wherein is formed a key-hole slot 22 through which an end of said spindle 19 projects, the reduced portion of the key-hole slot 22 being adapted to engage an annular groove 23 formed in said spindle 19 100 when said plate 21 is moved to locking position, and thus securely hold closure 16. By moving said plate 21 in the reverse direction said closure 16 is unlocked and may be withdrawn.

Each of said end closures is, in effect, composed of two discs 15, 15^a, and 16, 16^a, said disc being suitably spaced apart by means of a pair of parallel bars 24 between 110 which is adapted to slide a plate or bar 25 wherein is formed a longitudinal slot 26 and a lateral groove or channel 27.

In the inner disc of each end closure there is formed a slot 28, and on said disc there is created a circular projection 29, the circle, however, being broken at said slot 28 of the disc.

Disposed between and secured to said slides 25 is a handle piece 30, the slide 25 of said removable disc 16 being connected through a rod 31 which is screwed into the handle and is provided with a headpiece 32.

Adapted to slide on said spindle 19 is a tubular piece or sleeve 33 to each end of which is secured a disc 34 wherein are formed a plurality of radial slots 35. Said sleeve 33 is detachably connected with said spindle 19 by the aid of a lateral pin-like projection 36 provided on said spindle 19 with which pin a slotted portion 37 of the sleeve engages when the sleeve 33 is being slid on to the spindle 19.

Removably positioned in each pair of opposed slots 35 of said discs 34 is a razor blade 38 with carrier 39 (said carrier being a piece of sheet metal clamped on the non-shaving edge of the razor) the ends of which project somewhat beyond the discs 34.

Assuming the razor is not required for the purpose of shaving, the parts are in the positions shown in Figs. 1 to 5, when the blade 38^a is in alignment with the magazine slot 2, and the ends of its carrier 39 are lying in the lateral channels 27 of the slide bars 25; the cover plate 8 is shrouding the slot 2 of the casing or magazine, and its tongues 14 are snugly abutting the slotted pillars 3, 3.

When it is required to move said blade 38^a into shaving position said cover plate 8 is moved to unmask the casing or magazine slot 2 and the handle 30 is pushed, whereupon the slides 25 are projected and in their movement carry said blade 38^a to the guard 6, its movement being ultimately arrested when it enters the stop pieces 7 of said guard; said cover plate 8 is now moved back to shroud the casing or magazine slot 2, and the tongues 14 again move against the pillars 3, 3, so that ingress of soap or water to the interior of the razor is wholly or largely prevented.

Said tongues 14 also constitute, if necessary, positive supports for the blade which is thus prevented from accidental displacement.

To withdraw said blade 38^a into the casing or magazine again, the cover plate 8 is moved somewhat and the slides 25 are moved by the pulling of the handle 30, so that the blade 38^a is carried back into the casing or magazine 1, as shown in Figs. 1 to 5 of the drawings. To bring the next

succeeding blade 38 into position for use, said crank handle 20 is turned until it coincides or registers with the appropriate numeral of the disc 15, in which movement of the handle 20 the holder (comprising sleeve

and end discs) with its blades has been so revolved a step that the first mentioned blade 38^a has been carried out of the lateral channels 27 of the slides 25 and the ends of the carrier of the next succeeding blade 38 have been moved into said guide channels 27, said latter blade being thus disconnected from the holder and connected with the slides; this second blade is now ready for projection as before described to the shaving position shown in Fig. 6.

It is to be noted that said pillars 3, 3, form guides for the blade carrier 39 when a blade 38 is being projected or retracted.

As the ends of said blade carriers 39 move within the ring protuberance 29 of said end closures they are prevented from displacement and are positively carried to the lateral channels 27 of the slides 25 as and when required.

When it is required to withdraw a blade holder from the casing or magazine it is merely necessary to unscrew the rod or spindle 31 from the handle 30 somewhat when the disc 16, 16^a may be swung about said rod as a pivot clear of the casing 1 so that the holder may be withdrawn and a refill loaded into the casing or magazine without detachment of any of the parts of the razor handle portion; see Fig. 12 of the drawings.

It is to be clearly understood that I do not wish to confine myself to the particular mode of carrying my invention into effect as hereinbefore described, as various changes may be made in the construction without departing from the spirit and scope of the invention; and what I claim as my invention and desire to secure by Letters Patent is:

1. A safety razor which comprises a casing adapted to revolvably hold a plurality of shaving blades; a guard; and means whereby a shaving blade, in said casing may be radially carried to position for use, or withdrawn into said casing.

2. A safety razor which comprises a casing, a guard, a plurality of shaving blades revolvably disposed within said casing, and means whereby any selected shaving blade may be radially carried to position for use, or withdrawn into said casing.

3. A safety razor which comprises a casing, a guard, and means comprising slide members disposed at the ends of said casing, adapted, when actuated, to radially carry a revolvably mounted shaving blade previously moved into engagement therewith to position for use or withdraw it into said casing.

4. A safety razor which comprises a casing, a guard, slide members disposed at the ends of said casing adapted when actuated, to radially carry a shaving blade previously moved into engagement therewith to position for use or withdraw it into said cas-

- ing, a plurality of shaving blades, revolvably disposed within said casing, and means—such as the provision of lateral passages in said slide members—whereby any one of 5 said shaving blades, through revoluble motion, be engaged with or disengaged from said slide members.
5. In combination with a safety razor as claimed in the preceding claim 4, and in 10 which razor lateral passages are provided in said slide members, a shaving blade holder comprising a sleeve, adapted to fit on the spindle extending through said casing, and end discs having radial slots in which are 15 disposed shaving blades provided with carrier pieces the ends whereof project from said discs and are adapted to engage in or disengage from said lateral passages of said slide members on revoluble motion being 20 imparted to said holder.
6. In a safety razor as claimed in claim 3, a construction in which said guard is carried on pillars, which constitute guides for the shaving blades in their movement to or 25 from the guard.
7. In a safety razor as claimed in claim 3, and in which slide members are employed for the purpose specified, the provision on the end closure members of the casing of 30 circular projections whereby the blades are positively guided to and from said slides.
8. In a safety razor as claimed in claim 3,
- and in which slide members are employed for the purpose specified, a construction in which said slides are carried between end 35 closure discs.
9. In a safety razor as claimed in claim 3, means whereby a shaving blade holder with blades may be removed from or inserted in the casing without detachment of any of 40 the parts comprising the razor-handle portion.
10. For use in connection with a safety razor as claimed in claim 1, a shaving blade holder comprising a sleeve on the ends of 45 which are secured discs provided with radial slots which are adapted to receive razor blades and their carrier pieces, and means whereby said holder may be detachably connected with a spindle extending through 50 said casing.
11. In a safety razor as claimed in claim 3, and in which the guard is carried on pillars, a cover plate disposed on the casing and provided with means whereby a shaving blade is prevented from accidental displacement when in position of use.

In testimony whereof I affix my signature in the presence of two witnesses.

ALBERT EMANUEL GINSBERG.
